UNITED STATES PATENT OFFICE

CLYDE M. SHAW, OF MANHATTAN, KANSAS

DENT REMOVING TOOL

Application filed April 29, 1930. Serial No. 448,277.

This invention relates to an improved tool for removing dents from metal bodies, and it has more particular reference to an appliance of this classification which is expressly, but not necessarily, adapted for use in servicing garages and analogous repair stations to enable the user to straighten, smooth and substantially remove dents from metal bodies and fenders of automobiles so as to permit restoration of the repaired part to its original molded form.

The tool is so designed that it may be applied to any type or design of fender and to that end the tool is adjustable and reversible and permits action in almost every possible direction. It is so designed that the fender need not be removed from the car. The power required is human or hand power and requires no application of outside power, simply used by the hands of the operator and with human or body strength.

The tool is serviceable and used by the application of force and pressure developed by screwing the steel rod and in this manner bringing the rollers into place where required on the damaged fender or indented body or fender and after the tool has been thus adjusted, by movement and manipulation by the operator, the rollers are so applied as to press and force the metal back into place as originally molded or pressed and restoring the same to its original form and mold. Pressure may be readily applied or released as the operator may desire and large or smaller rollers may be used to adapt the use of the machine to the size and type of fender and as the size of the dent or damage to the fender may require.

Another feature and advantage of the device is that it is susceptible of being employed expeditiously and in a feasible manner by either skilled or unskilled hands, to restore fenders and body dents in a scientific and usable manner, and to provide a tool that is at once usable, serviceable, and characterized by exceptional simplicity in construction and adaptability.

In the drawings:

Figure 1 is an elevational view of a tool

constructed in accordance with the present invention.

Figure 2 is an edge elevational view of the same.

Figures 3 and 4 are cross sectional views taken on the lines 3—3 and 4—4 of Figure 1.

Figure 5 is a view of the lower end portions of the companion jaws showing a pair of complementary work-engaging accessories.

Figures 6 and 7 are detail elevational views of additional agents or accessories which are interchangeable in an obvious manner.

In the drawings, in Figure 1 the frame is generally designated by the reference character 8 and this comprises a pair of symmetrical companion bar members or sections 9 and 10 of general L-shaped configuration. The inturned short arms are coupled together through the medium of a coupler 11 at the top. This coupler is centrally apertured to provide a guide for passage of the smooth stem portion 12 of the adjusting shaft 13. Incidentally the lower end portion of the shaft is enlarged and formed with opposite sets of screw threads 14 and 15 respectively.

On the upper end of the shaft is a handle 16 of appropriate design. On the lower end portion of the bars 9 and 10 are fittings 17 each of which includes a right-angularly disposed collar 18 functioning as a socket for reception of the stem 19 of the complementary appliance or accessory generally designated by the numeral 20. The accessory comprises a stem 19 and a substantially U-shaped yoke 21, whose arms are formed with bearing holes 22 to accommodate the ends of the pin 22 on which the surfacing and pressing roller 23 is mounted for rotation.

These devices 20 are used in opposed pairs. There are other interchangeable accessories also employed. For example, as seen in Figure 5, the numeral 24 designates a substantially semi-circular tire grip designed to partly embrace a conventional automobile tire and having a stem portion 25 and a pivotal connection 26. It will be noted that in each instance a set screw 27 is provided for holding the stem in place. I might mention also that substitute rollers are provided. For instance, the roller 28 in Figure 6 or the roller 29 in

Figure 7 may be substituted for the truly cylindrical type of roller 23 already described.

Any number of suitable attachments will of course be provided to accommodate the particular character of metal work being reconditioned.

The numerals 30 designate sleeves slidably adjustable on the arm portion of the parts 9 and 10 these sleeves being held in set position by the set screws 31. Duplex toggle connections are provided between screw threaded portions 14 and 15 and the sleeves. Each toggle comprises suitably connected and arranged operating links 32 pivotally connected at their outer ends with the respective sleeves and pivotally connected at their inner ends with the feed blocks 33 adjustably arranged on the opposite screw threaded portions 14 respectively. This arrangement provides the desired expansion and contraction of the parts 9 and 10 through the medium of the toggles and adjustable sleeves.

Thus the attachments on the ends of the jaws may be properly engaged with the fender or other work being re-shaped or repaired.

It is evident from the foregoing description and drawings that I have evolved and produced a novel rolling and bending tool for metal work which is especially designed for reconditioning automobile fenders and the like.

The gist of the invention is in the provision of a suitable arrangement of jaw supporting members coupled together in appropriate pivotal relationship and so shaped and designed as to permit them to properly apply the rolling and pressing accessories to the parts being acted on. The fittings or fixtures on the jaw supporting members are so standardized and made uniform as to accommodate the diversified types of attachments or appliances which are to be mounted on the members for appropriately engaging the different curvatures of work. The interchangeability and standardized features are important.

Then too, the bodily adjustable toggles mounted on the intermediate portions of the long arms of the jaw supporting members 9 and 10 is a noticeable improvement, particularly when taken into conjunction with the independent adjustment of the toggling rendered possible through the double acting screw and feed block connection with the links of the toggle structure.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field

of invention claimed may be resorted to in actual practice if desired.

I claim:

1. In a repair tool of the class described, a pair of substantially duplicated L-shaped jaw supporting members having inturned short arms disposed in close spaced relationship, a pivoting and connecting device coupling said ends together, expanding and contracting means for the members, said means including sleeves slidably carried on said members, means for securing the sleeves in longitudinally adjusted position, a shaft mounted slidably and rotatably in said connecting device and having operable connection with said expanding and contracting means, and work engaging appliances carried by the free end portion of the jaw supporting members.

2. In a tool of the class described, a pair of complementary substantially L-shaped members having their short arm portions directed inwardly toward each other; a connecting device coupling said arms together, said device having a central guide opening, work engaging means mounted on the free end portions of the long arms of said members, sleeves adjustably mounted on the intermediate portions of the long arms, means for securing the sleeves, in adjusted position on the members, a shaft having a smooth portion extending rotatably and slidably through the guide openings in said connecting device, the shaft being provided on one end with a handle and on the opposite end with a double feed screw, feed blocks mounted on the screw-threaded portions of the feed screws for opposite movement, and links pivotally connected with the blocks and also pivotally connected with said sleeves.

In testimony whereof I affix my signature.

CLYDE M. SHAW.
